United States Patent

Des. 240,067
Patented May 25, 1976

240,067

PLANTER OR SIMILAR ARTICLE

Robert Seymour Peets, Watchung, N.J., assignor to
The Singer Company, New York, N.Y.

Filed Feb. 27, 1975, Ser. No. 553,707

Term of patent 14 years

Int. Cl. D11—02

U.S. Cl. D35—3 B

Fig.2

Fig.1

Fig.3

Fig. 4

Fig. 5

Fig. 6

FIG. 1 is a front elevational view of a planter or similar article showing my new design,

FIG. 2 is a top plan view thereof,

FIG. 3 is a bottom plan view thereof,

FIG. 4 is a rear elevational view thereof,

FIG. 5 is a left side elevational view thereof, and

FIG. 6 is a right side elevational view thereof.

I claim:

The ornamental design for a planter or similar article, substantially as shown.
